LUBRICANT PURIFYING APPARATUS AND
INDICATOR

Samuel Donald Perlman, Washington, D. C.

Application April 25, 1944, Serial No. 532,690

2 Claims. (Cl. 184—6)

1

This invention relates to a structurally and functionally improved purifying and indicating apparatus and in its more specific aspects aims to provide a structure which will be of particular utility when applied to a motor-driven vehicle and for the purposes of purifying the lubricating oil circulating through the engine system, as well as indicating to the operator the condition of that oil.

It is an object of the invention to provide an apparatus of the foregoing type and by means of which particles of foreign matter, as well as diluents will be constantly removed from the oil stream as it circulates incident to the operation of the motor of the vehicle. Accordingly, not alone will substances which might act to clog the system or as abrasives in connection with the moving parts of the motor be removed from the oil, but also to a great extent acids and water will also be removed from the oil stream.

A further object is that of furnishing an apparatus of this type by means of which an operator may at all times be cognizant of the condition of the lubricant. Therefore, he will be able to readily determine when it is necessary to either renew the body of oil or the purifying portion or portions of the apparatus.

Another object is that of designing an oil-purifying and indicating apparatus by means of which the operator may, with minimum effort, control the oil flow so that he may inspect the body of the oil as it circulates and without such body being subjected to any purifying action. Accordingly, it will be feasible for him to determine, for example: first, whether the oil body is in a condition such that it requires renewal; second, whether the purifying or filtering unit has absorbed all of the foreign particles or diluents which it is capable of receiving; and, third, whether that unit is, in effect, offering an obstruction to the oil flow such that it should be shortly or immediately renewed to prevent the damage occurring to the motor parts requiring lubrication.

Still another object is that of furnishing an apparatus and system of this type which may be applied to motors as heretofore constructed and without requiring any major alterations or revisions of the structure of the latter.

With these and other objects in mind, reference is had to the attached sheet of drawings illustrating one practical embodiment of the invention, and in which:

Fig. 1 is a somewhat diagrammatic view illustrating a general layout of motor such as oc-

10 curs in a motor vehicle together with the dash of such vehicle and showing the improved structure of the present invention applied thereto;

Fig. 2 is a face view of the indicating mechanism which may be associated with the dash; and

Fig. 3 is a transverse sectional view taken along the lines 3—3 and in the direction of the arrows as indicated in Fig. 2.

15 In these views, the reference numeral 10 indicates a motor of any desired design and which is provided with the usual oil pump 12. The dash portion 11 of the motor vehicle has also been shown in this view and, moreover, there has been diagrammatically indicated a line extending from the pump 12 and which has been identified by the numeral 13, as well as a line 14 which is connected to the parts of the motor requiring a circulation of oil. As will be understood and in 20 the usual manner, with the motor operating the pump 12 will function to force oil from, for example, the sump portion of the crank case into the oil-supplying line 13. Assuming this line to be connected with oil-delivering line 14, the oil 25 is thereupon distributed to the several parts of the motor from which it is returned to the sump portion. This cycle is repeated indefinitely with the motor operating.

As also shown in this view, a filtering and 30 purifying unit is conveniently disposed in advance of the dash 11. This unit may include a casing 15 provided with, for example, a draining plug 16. A cover 17 may be removably applied to the casing and permit of access to the 35 interior thereof. Located within the casing is any desirable and proper type of filtering or purifying unit or units. These may take any proper form of construction and when interposed in the oil flow will serve to remove foreign 40 particles from the body of the oil. Moreover, the body of the filtering material will, to a greater or lesser extent, remove from the oil body diluents such as water and acid. It is intended that periodically the cover 17 be removed and the 45 filtering body contained therein be either discarded and replaced with a new unit or that such body be otherwise renewed and rendered suitable for continued functioning.

As will be seen, the pipe 13 extends towards the 50 casing 15. Interposed within this pipe is a valve 18, which may be of the "four-way" valve type. According to the present invention, it is preferred that such a valve control be provided and that there extend from the valve housing lines 19 and 55 20 through which the oil distributed from the line

13 may be alternately diverted. An actuator 21 extends from the valve. With the parts in the position illustrated, the oil flow will be from the pump 12 to the line 19 and thence through the filtering unit or casing 15 to the line 20. With the actuator 21 shifted to its second position, the oil flow will occur directly from the line 13 to the line 20. In either event, the oil flow will continue from the line 20 to the line or pipe 14; these two lines being connected as hereinafter brought out.

It is preferred that the flow normally be from line 13 through line 19 and the casing 15 to the line 20. With this thought in mind, an actuator such as a flexible cable 22 may be secured to the handle 21. This actuator extends through the dash 11 and has secured to it a knob 23. With the knob disposed at a point adjacent the dash, the wire 22 will maintain the valve 18 in the desired position. If this knob or equivalent portion is projected or pulled towards the operator, then the wire 22 will cause the actuator 21 to be shifted. This will correspondingly move the valve and cause a direct flow of fluid from the line 13 to the line 20, thus by-passing the casing 15.

Now referring to Figs. 2 and 3, it will be seen that a preferred form of indicating mechanism may include a housing 24. This housing may embrace a reflector portion 25 within which there is disposed a lamp 26. In advance of this lamp, a transparent tube 27 is disposed. The ends of this tube are respectively connected to the lines 20 and 14. Further tubes 28 and 29 may be arranged one to each side of the tube 27. These tubes 28 and 29 may also be transparent but are preferably colored to correspond to the coloration of oil when the latter is respectively in unsuitable condition for lubricating purposes or in a suitable condition for such purpose. Arranged adjacent the tubes 27, 28 and 29 is a partition member 30 which may be formed with slits through which a greater or lesser portion of the tubes are visible. This partition also acts as a mask for the light 26. As shown in Fig. 2, the face of the partition which is directed towards the operator may have their own indicia such as 31 indicating respectively the characteristic of the different colorations embodied in tubes 28 and 29.

With the parts functioning in the preferred manner (i. e. with line 13 connected to casing 15), the oil flowing from the purifying unit will pass through the tube 27. Due to the fact that this tube is preferably uncolored, the operator will be able not alone to observe the oil flow but will be cognizant of the color of the oil body passing through the tube 27. He will instinctively compare such coloration with the coloration of tubes 28 and 29 or any equivalent indicating portions. So long as the body of oil maintains a coloration substantially equivalent to that of, for example, tube 29 no concern need be felt. However, should such coloration approach or equal the tint of tube 28, he will know that the body of oil within the motor crank case should be renewed. Also, he will realize that the body of the filtering unit may require renewal. The operator will then act according to the warning and indications thus received.

If for the purpose of satisfying himself that the filtering unit is functioning properly he desires to by-pass such unit for a temporary period, the actuator 23 may be shifted. Thereupon, oil will flow directly from the line 13 to the line 20 and so through the tube 27. If the oil flow there-

tofore through that tube has been relatively sluggish, he will immediately become cognizant of the fact that the filtering unit requires renewal. Also, if under these circumstances the color of the oil darkens, he will realize that the filtering unit is functioning to remove impurities from the oil. Thereupon, the actuator 23 may be returned to its normal position.

If the indications are such that the operator is rendered aware of the fact that the filtering unit is, for example, clogged and therefore that insufficient oil is reaching the moving parts of the motor, he may, of course, leave the knob 23 in its extended position. Under such circumstances, the oil will by-pass the unit 15 and circulate in the usual manner direct to the line 14 and thence to the bearings. Thereupon, the operator will renew the body of the filtering unit within the casing 15 at the earliest moment.

As will be appreciated, any desired substitute construction might be employed in lieu of the elements 28 and 29 heretofore described as tubes. Preferably, however, these elements will be transparent so that light rays may pass through the same. If such a structure is not desired, the partition member may, if necessary, include representations of various colorations, thus permitting of dispensing with the separate elements. Also, while the drawings indicate that all oil passes through the purifying unit, such unit and the pipes extending therefrom may be connected to the lubricating system of the motor in any one of a number of acceptable manners.

Thus, it is obvious that, among others, the several objects of the invention as specifically afore noted are achieved. It is apparent that numerous changes in construction and rearrangements of the parts might be resorted to without departing from the spirit of the invention as defined by the claims.

I claim:

1. An apparatus of the character described for connection to the lubricating system of a motor and which system includes an oil-supplying line, an oil-delivering line and means for inducing a flow of oil through said lines, said apparatus including a transparent tube connected to said delivering line and disposed at a point where the passage of lubricant therethrough may be observed by the operator of the motor, an oil purifying unit formed with an inlet and an outlet, a single "four-way" valve and casing therefor, lines for connecting said valve with the oil-supplying line of said system, the inlet and outlet of the purifying unit and said transparent tube and means for shifting said valve whereby oil may be caused to flow from the line connectable with the oil-supplying line through said valve, thence through the purifying unit and the transparent tube and under an additional shifting of said valve, may be caused to flow directly from the line connected with the oil-supplying line through the valve to said transparent tube.

2. An apparatus of the character described for connection to the lubricating system of a motor and which system includes an oil-supplying line, an oil-delivering line and means for inducing a flow of oil through said lines, said apparatus including a transparent tube connected to said delivering line and disposed at a point where the passage of lubricant therethrough may be observed by the operator of the motor, an oil purifying unit formed with an inlet and an outlet, a single "four-way" valve and casing therefor, lines for connecting said valve with the oil-

supplying line of said system, the inlet and outlet of the purifying unit and said transparent tube and means for shifting said valve whereby oil may be caused to flow from the line connectable with the oil-supplying line through said valve, 5 thence through the purifying unit and the transparent tube and under an additional shifting of said valve, may be caused to flow directly from the line connected with the oil-supplying line through the valve to said transparent tube; said shifting means extending to a point adjacent said transparent tube.
